Primary Examiner — Clare E Heflin(74) *Attorney, Agent, or Firm* — Renner, Otto, Boisselle & Sklar, LLP(57) **CLAIM**

The ornamental design for a luminaire, as shown and described.

DESCRIPTION

FIG. 1 is a perspective view of the luminaire according to my new design;

FIG. 2 is a side view of the luminaire shown in FIG. 1;

FIG. 3 is a top view of the luminaire shown in FIG. 1;

FIG. 4 is a bottom view of the luminaire shown in FIG. 1;

FIG. 5 is a perspective view the luminaire showing a variant of my new design;

FIG. 6 is a side view of the luminaire shown in FIG. 5;

FIG. 7 is a top view of the luminaire shown in FIG. 5; and,

FIG. 8 is a bottom view of the luminaire shown in FIG. 5.

The broken lines shown on the drawings depict portions of the luminaire that form no part of the claimed design.
